UNITED STATES PATENT OFFICE.

JOHN W. SOUDERS AND JOSEPH PRUTZMAN, OF MUNCIE, INDIANA.

BRICK AND TILE KILN.

SPECIFICATION forming part of Letters Patent No. 289,938, dated December 11, 1883.

Application filed June 21, 1883. (No model.)

To all whom it may concern:

Be it known that we, JOHN W. SOUDERS and JOSEPH PRUTZMAN, citizens of the United States, residing at Muncie, in the county of Delaware and State of Indiana, have invented 5 a new and useful Improvement in Kilns for Burning Brick, Tile, &c., of which the following is a specification.

Our invention relates to improvements in 10 kilns for burning brick, tile, &c.; and it consists in a particular form and apparatus for generating and retaining heat, and the object being to facilitate and cheapen the burning of brick, &c.

15 Figure 1 is a vertical side view, partly in section; and Fig. 2 is a cross-section taken on different lines.

Similar letters refer to similar parts throughout the several views.

20 It will be seen in Fig. 2 that one side of the kiln is cut down through the line *x x* and the other side through the line *S S*.

The kiln consists, mainly, of the side walls, 25 *F*, and furnaces *C C*. The furnaces are divided into rooms by partition-walls *I*, as shown in Fig. 1. Each room consists of two rows of arches, *i*, side by side, and extending backward to the wall or base *H*. These arches are set apart, leaving spaces *s s* between them. On 30 these arches the brick floor *f* is laid, the back part of which is made tight, while in the front spaces *f'* are left between the brick, so as to admit a free current of air up through the arches and floor. The said floor is laid of 35 brick set up edgewise, the row directly over the center of the two arches being laid crosswise of the furnaces, as shown in section *x x* of Fig. 2, and by solid or black brick *f''* in Fig. 1, the others being laid lengthwise of 40 the furnaces over the spaces *s* left between the arches, as shown, by solid brick in Fig. 2.

The base or floor *H* of the kiln is made of some solid substance, on which the brick or tile are placed to burn.

45 On each side of the furnace-rooms are the walls *I*, covered over by the arches *T*. In

the front of the furnaces are the doors *A*, and in the back walls are the openings *d* and flues *D'*, the openings *d* leading into the body or lower part of the kiln, where the brick or tile are placed, and the openings or flues *D'* leading up and entering into the body of the kiln above the furnaces, all as shown in Figs. 1 and 2. A brick, *D*, is placed over the opening *D'*, so that it may be drawn out, as shown 55 in dotted lines, to allow a draft of heated air or fire to enter the upper portion of the kiln, or closed, as shown in Fig. 2. The openings *d* are made in a **T** shape, as shown in Fig. 2, with a downward projection, *g*, which causes 60 the draft to strike downward as it passes through the said opening, as shown.

As thus described, the fuel is placed in the several furnace-rooms upon the floor *f*, and the draft comes in at the opening *B* up through 65 the floor *f*, and into the kiln through the openings *d*. When it is desired, the heat may be passed into the upper portion of the kiln through the flues *D'*. The flues *D'* at each end of the kiln are placed at the outside corner 70 of the furnace instead of the center, as in the other furnaces, all as shown in section part of Fig. 1. The ends of the kiln may be built up in the usual form, and the number of furnaces on a side may also be varied as desired. 75

Having thus described our invention, we claim and desire to secure the following by Letters Patent:

In a kiln, the combination, with the rooms consisting of parallel arches formed with air spaces between them, of an open floor, a flue, *d*, for the admission of air to the bottom of the kiln, and a flue, *D'*, provided with a brick valve, *D*, for regulating the admission of air to the upper part of the kiln, substantially as 80 set forth.

JOHN W. SOUDERS.
JOSEPH PRUTZMAN.
